SEWING MACHINE LID AND ANTI-SKID COVER THEREFOR

Minnie L. Aulds, Rte. 1, Harlingen, Tex.

Filed Dec. 4, 1957, Ser. No. 700,611

4 Claims. (Cl. 45—68.3)

This invention relates, broadly and generally construed, to a sewing machine, but more particularly to the type which is characterized by a leg-supported table having, as is customary, a hingedly mounted, fold-away lid which, when folded, functions as a cover for a receding machine and, when extended to assume a horizontal position, serves as a utility shelf providing, as is desirable, an accessible work surface.

More specifically, the concept has to do with the above named lid and means whereby the work surface may be better utilized, that is, to its utmost advantage and so that it will accordingly measure up to the requirements of practical service to a housewife, seamstress or other user of the machine.

It is a matter of common knowledge that the flat top and bottom surfaces of the aforementioned shelf-forming lid are smooth and highly polished, in keeping with every-day furniture demands. When the lid is being used as a work surface or shelf, a problem often presents itself. That is to say, when the user of the sewing machine is sewing and stitching silk and satin-finished cloth and garment materials, no satisfactory way exists whereby the slippery surfaced material will "stay put." Under the circumstances, it invariably shifts aimlessly about and in many instances where the piece of cloth is of appreciable size or area, it will often become accidentally displaced, exasperating the worker. It is perplexingly difficult to cope with this problem, since a solution thereof would fall short, it is believed, if the shelf work surface were coated, covered or prepared in some manner to present an anti-skid surface. That is to say, there are times when shiftable movement of the work piece which is being sewn should not be hindered or hampered.

When, however, slick-surfaced material is being worked on, it is highly undesirable that it be permitted to move and shift about recklessly. An objective in the instant matter is to offer what is believed to be a satisfactory compromise wherein the surface may be allowed to remain smooth and glossy when desired or, when preferred, transform, temporarily so to speak, into a surface which is skid-resisting and otherwise presented to measure up to the needs of practical service to the user in pursuit of her often perplexing sewing and simultaneous holding tasks.

In carrying out the underlying principles which have given rise to an incentive to solve the problem, the concept, in a combination sense, has to do with a sewing machine embodying a horizontal machine-supporting table provided with a horizontal shelf extending outwardly from that end of the table adjacent the working position of the user of the machine, said shelf having a flat work surface coplanar with the top of the table, said surface embodying taut but pliant skid-resisting means which functions to cause a slick-surfaced piece of work to temporarily adhere and cling thereto, whereby

2

to thus prevent the same from becoming perplexing displaced while it is being sewn and otherwise handled.

Novelty is predicated on the above ways and means and wherein said means comprises a simple, practical and economical fabric slip cover. More particularly, the cover is a snug-fitting, readily applicable and removable terry cloth jacket which is slipped into place when needed and quickly removed when not in use and folded up and stored away in an available drawer 10 of the table structure.

Other objects, features and advantages will become more readily apparent from the following description and the accompanying drawing.

In the drawing, wherein like numerals are employed 15 to designate like parts throughout the views:

Fig. 1 is a perspective view showing the sewing machine, that is, the table and a portion of the machine in perspective, and emphasizing the fold-away, horizontally disposed hinged utility shelf which is commonly 20 referred to as the cover or lid, the anti-skid jacket being illustrated and positioned on the lid for use.

Fig. 2 is a central longitudinal sectional view on an 25 enlarged scale taken on the plane of the line 2—2 of Fig. 1 looking in the direction of the arrows.

Fig. 3 is a perspective view of the jacket per se.

With reference to Figs. 1 and 2, the table portion of the sewing machine is denoted generally by the numeral 6, the top thereof being denoted at 8 and the receding machine proper at 10. Hingedly attached to one 30 transverse end portion of the top, as at 12, is the significant fold-away lid 14 (Fig. 2). This is the customary hingedly mounted lid which, when it is extended beyond the end of the table, is coplanar therewith and provides 35 a utility shelf and work surface. As before mentioned, both surfaces, as usual, of the lid are highly polished, and consequently slippery. Whereas this surface is highly desirable under certain working conditions, there are other conditions when, as before mentioned, it is, to 40 say the least, perplexing and given to trying the patience of the worker. Whereas and as before touched upon it would be within the purview of this concept to provide any suitable means as a temporary cover for the work surface when one is sewing slippery materials, it 45 is preferred that this "surface" be applicable and removable. To achieve this end and after much experimentation and trial and error efforts, it has been concluded that a simple, practical and economical slip cover, more specifically a snug-fitting, expandible and contractable jacket, is desirable. The jacket is denoted generally by the numeral 16 and is rectangular in form having top and bottom walls 18 and 20. At times, the cover 50 has also been, perhaps properly so, referred to as a shelf or lid attachment in the form of a bag. To prevent 55 displacement, the left hand end is closed at 22, while the right hand end is open at 24. At the open end, and suitably attached either directly or by way of a hem, there is an elastic binder 26. This edges the mouth and, in addition, provides additional elastic retentive 60 properties assisting in holding the cover or jacket in place when used as seen in Figs. 1 and 2.

The jacket is preferably constructed of terry cloth of appropriate elastic properties. When the bag is off, it is narrower in width than the shelf or lid 14. When 65 it is applied, it stretches and the inherent elastic properties function to taunt and retain the slipcover in the given position. The nap (not detailed) may be of such looped form that it presents the desired softness and pliancy while yet offering the skid-resisting properties 70 desired. It will be evident that when the jacket is applied, it is distended and amply taunted to remain in

its given self-retaining position. It is of prescribed size and proportional to the size of the lid on and over which it is slipped to assume its intended usable position. It is launderable that it may be kept spotless and clean and is also reversible so that either the top or bottom walls 18 or 20 may be brought into play. Because of the soft interior, there is no likelihood of the glossy surface of the lid being smeared or in any manner scratched or otherwise impaired.

It is repeated, that the concept has to do with the transformable work surface of a fold-away lid on a sewing machine table, and preferably wherein that surface, being temporarily applicable and removable, is presented through the medium of a simple and economical on-and-off terry cloth jacket.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. For use on a hinged fold-away lid such as is employed on currently used table-type sewing machines; a cloth jacket adapted to snugly encase said lid, said jacket comprising a slipcover made of expandable and contractable terry cloth and being open at one end and closed at the other end, said slipcover being of prescribed size and proportional to the size and shape of said lid so that when in operating position on said lid it is then distended and self-retaining, the exterior nap surfaces being skid-resistant.

2. For use on a hinged fold-away slippery-surface lid such as is commonly employed on currently used receding-type sewing machines; a terry cloth slipcover constituting a lid encasing jacket and which is open at an inner end and closed at the outer end, said jacket being pliant, self-adjustable and skid-resistant, expandable and normally narrower than the lid, whereby when it is slipped endwise of the lid it stretches and retains itself in its given position, and also spreads and tautens

itself in a manner to provide the usable surface of said lid with a practical anti-skid work surface.

3. In combination, a sewing machine embodying a horizontal machine-supporting table provided with a horizontal shelf extending outwardly from that end of the table adjacent the working position of the user of the machine, said shelf having a flat work surface embodying taut but pliant skid-resisting media which functions to cause a slick-surfaced piece of work to temporarily adhere and cling thereto and to thus prevent the work from becoming perplexingly displaced while it is being sewn and otherwise handled, said media spanning the entire working surface and providing a self-adjustable skid-resistant area which, while it causes the garment or other piece of work to stay put, does not hinder the intended shiftable movement thereof that may be needed and required by the worker.

4. In combination, a sewing machine embodying a horizontal machine-supporting table provided with a horizontal shelf extending outwardly from that end of the table adjacent the working position of the user of the machine, said shelf comprising a hingedly mounted lid having the additional function of a cover for the machine itself when the latter is not in use, the surfaces of said shelf, having been highly finished and polished, being such that the top side of the shelf permits unhampered gliding and movement of a piece of work thereon, and means for temporarily transforming said top side into a nonslippery work surface, said means comprising a tautened snug-fitting slipcover stretched and spanning said top side, said slipcover being constructed of launderable terry cloth and being open at one end and closed at the other end.
